UNITED STATES PATENT OFFICE.

EDWARD A. CUNNIFF, OF WALTHAM, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed June 19, 1926. Serial No. 117,163.

This invention relates to feeler mechanisms for looms, whereby on substantial exhaustion of the filling in the shuttle, the operative condition of the loom is changed.

5 In looms of the filling replenishing type, it is now the common practice to provide a feeler mechanism which shall feel for the filling in the shuttle at times and upon detection of substantial exhaustion of filling, set 10 in operation a train of mechanism for effecting replenishment of the filling prior to complete exhaustion.

Feeler mechanisms of whatever type should act reliably to call for a change of 15 filling only when the filling in the shuttle has reached a degree of substantial exhaustion, and since the amount of filling that remains upon the filling carrier or bobbin after replenishment constitutes waste and 20 consequent loss, attempts have been made to render the feeler mechanism delicate both to the presence and substantial absence of filling on the bobbin.

One of the objects of the present invention is to provide a feeler mechanism that 25 shall possess such delicacy of filling detection that the minimum amount of waste may remain upon the filling carrier or bobbin when it is ejected from the shuttle on filling 30 replenishment.

Another object of the present invention is to provide a feeler mechanism of the side slipping type wherein the delicacy of feeler action may be such that side slipping movement of the feeler may take place only when 35 a minimum amount of filling remains upon the filling carrier or bobbin.

Another important feature of the present invention consists in a floating side slipping 40 feeler mounted upon a feeler stand for movement towards and from the front of the loom relatively thereto and in a direction longitudinally of the shuttle, and to associate the feeler and feeler stand and their respective mountings in a manner that will cause the feeler stand itself to be moved 45 frontwardly only when the feeler partakes of its side slipping movement on a detecting beat.

50 In accordance with one aspect of the present invention, the feeler stand is mounted for movement towards and from the front of the loom and is normally held in its rearward position for the support of the side slipping feeler in its movements towards and

from the front of the loom and longitudinally of the shuttle, and is caused to be moved frontwardly by the forward movement of the feeler only when the feeler itself has detected substantial exhaustion of the filling in the shuttle. In this connection, also, the present invention associates with the feeler stand means for changing the loom operation or filling replenishment whenever the feeler stand is itself moved frontwardly 65 by the feeler.

The invention and new combination of parts and novel features thereof will best be made clear from the following description and the accompanying drawings of one good 70 practical form thereof.

In the drawings:

Fig. 1 is a perspective view of parts at the feeler side of a loom provided with the present invention;

75

Fig. 2 is a perspective view showing parts of the feeler mechanism separated but ready for assembly;

Fig. 3 is a plan view showing the relation of parts of the feeler mechanism when a 80 working supply of filling is present in the shuttle on a detecting beat; and

Fig. 4 is a view similar to that of Fig. 3, showing the relation of parts when the feeler detects substantial exhaustion of filling in 85 the shuttle on a detecting beat.

The details of the means for changing the operative condition of the loom, such, for instance, as replenishment of filling, are not herein shown and described, because such details form no essential part of the present invention and are now well understood by those familiar with this character of mechanism.

The loom frame 1 may be of usual construction and provided with the shipper stand 2 in which is movable the shipper 3, and extending up from the usual transverse or rock shaft at the front of the loom (and not herein shown) is an arm 4 to which is 90 pivotally connected at 5 the actuator 6, the rear end portion 7 of which is adapted to be engaged at times by an operating member 8 herein shown as movable with the cam follower.

105

Pivottally mounted on the loom frame or a bracket 9 secured to the shipper stand is the transmitter 10 adapted to rock on the pivotal support 11 and having an actuator positioning pin 12. Extending laterally 110

from the pivotal support 11 in a direction opposite the arm 10 is the arm 13 to which is adjustably secured the bracket 14 by means of a bolt 15, and said bracket 14 is 5 provided with an opening 16, the lower arm 17 of which has a cam surface 18.

Extending through the opening 16 is the supporting arm 19 pivotally mounted on the vertical stud 20 which may be conveniently 10 supported on the shipper stand. Coiled about the stud 20 is a spring 21, one end of which is secured to a fixed part at 22, and the other end of which at 23 acts upon the supporting arm 19 and normally maintains the said arm in its rearward position. The parts so far described may be of usual construction and are now well understood in the art.

The outer end portion of the supporting 20 arm 19 is provided with a plate 24 to which is adjustably secured the feeler stand 25. In the present instance of the invention the plate 24 is provided with slots 26 through which may be passed the securing bolts 27 25 for holding the feeler stand 25 in desired position upon the supporting plate.

The feeler stand 25 is constructed for the direct support of the floating and non-pivotaly mounted feeler 28, so that the feeler 30 may have movement upon the feeler stand in a direction towards and from the front of the loom and longitudinally of the shuttle, as will more fully appear.

In the present instance of the invention, 35 the feeler stand 25 has the side guide portions 29 which act upon portions of the feeler 28 to direct its movements towards and from the front of the loom, and yet permit longitudinal movement of the feeler with relation to the shuttle.

The feeler 28, as hereinbefore noted, is of the floating non-pivotal side-slipping type and is provided with a laterally projecting arm 30 which extends beneath or into the 45 guiding portion of one of the guides 29, while the opposite side of the feeler is provided with a toe portion 31 which is similarly received in the guide 29, the construction being such that when the feeler is moved 50 frontwardly by a working supply of filling on a detecting beat, it may be held in its floating non-pivotal relation to the feeler stand by the interengagement of the guides 29 and the projection and toe 30 and 31 respectively. It has been found practical to 55 form the feeler stand 25 as a plate having the holes 32 through which, and the slots 26 of the plate 24, the securing belts 27 may be passed to receive the nuts 33 beneath the plate 24. This construction and formation 60 of the feeler stand and supporting plate and the means for holding them in operative relation may of course be varied within the true scope of the present invention.

65 The feeler 28 is normally under the in-

fluence of a spring 34, one end of which is directly connected to the feeler at 35, and the other end of which is connected to a lug 36 at the rear portion of the feeler stand, the construction being such that the normal 70 tendency of the spring 34 is to move the feeler rearwardly relative to the feeler stand into its feeling position.

Mounted upon the feeler stand is a stop or projection 37 which engages the laterally 75 extending arm 30 at a point adjacent its connection with the feeler 28, so that the stop 37 acts to limit the rearward movement of the feeler under the influence of the light spring 34 which, as shown in the 80 present instance of the invention, acts diagonally with a pulling effect upon the feeler to move it into its rearward feeling position.

Extending upwardly from the feeler stand is a second stop 38 which acts upon the feeler 85 28 to limit its swinging movement into its true feeling position under the action of the spring 34. From the construction thus far described, it will be apparent that the feeler 28 floats upon and is directly supported 90 by the feeler stand for free movement except as controlled by the light spring 34, in a direction towards and from the front of the loom and longitudinally of the shuttle,

and that the stop 37 which acts upon the projecting arm 30 adjacent its connection with the feeler, serves to determine the rearward position of the feeler, while the stop 38 serves to position the swinging movement of the feeler into its proper feeling position 100 under the action of the spring 34. It is desirable in most cases to position the two stops 37 and 38 as shown, and preferably to locate the stop 38 adjacent the point where the end of the spring 34 is connected directly to the feeler, but this may not always be necessary.

The feeler 28, shown in Figs. 1 and 2 in its rearward feeling position, is provided with a lug or finger 39 which on frontward and rearward movement of the feeler travels in an opening 40 formed in the guide 29, and extending from the plate 24 or feeler stand support is a lug 41 which may be secured either to the plate 24 as shown or some other part of the arm 19, the essentials in this respect being that when the feeler is moved frontwardly on a detecting beat with a working supply of filling in the shuttle and the feeler consequently does not partake of its side swipe movement, the lug or finger 39 will not engage the lug 41, with the result that the feeler will be moved frontwardly on the feeler stand, while the feeler stand itself will remain in its rearward position under the impulse of the spring 21. This condition is illustrated in Fig. 3 where it will be noted that the feeler 28, the rear end portion of which is provided with the usual teeth 42, has been moved frontwardly 130

by a working supply of filling 43 on the filling carrier or bobbin 44, and it will be noted that the lug or finger 39 passes by the lug or projection 41 without engagement therewith, and this condition maintains during weaving so long as a working supply of filling is in the shuttle.

When the filling has become substantially exhausted, as indicated in Fig. 4, the feeler 28 will be no longer held from side slipping movement by the now substantially depleted filling and as the lay moves frontwardly the feeler 28 will side slip, thereby operatively positioning the lug or finger 39 on the feeler with the lug or projection 41 on the feeler stand support, with the result that the feeler stand support itself will now be moved frontwardly, thereby carrying the arm 19 frontwardly over the cam portion 18 of the transmitter and perforce moving the end 7 of the actuator 6 into operative relation with the operating member 8 to thereby effect replenishment of filling.

As usual in feeler looms of the type herein shown, the lay is provided with the shuttle box 45, Fig. 1, the front wall of which is provided with an opening 46 which registers with an opening 47 in the front wall of the shuttle 48 when the latter is properly boxed, the condition being such that the feeler may enter the shuttle and feel for the filling.

During weaving when a working supply of filling is present in the shuttle on detecting beats, the feeler will be moved frontwardly on and relative to the feeler stand and the lug or finger 39 on the feeler will not engage the projection or lug 41 on the feeler stand support, and consequently the feeler stand will remain in its rearward position under the influence of the spring 21. When, however, the filling has become substantially exhausted, as indicated in Fig. 4, the feeler will side slip on contact with the filling carrier or bobbin and cause the finger or lug 39 to become operatively positioned with respect to the lug 41 on the feeler stand support, and on frontward movement of the feeler thereafter the feeler stand itself will be moved frontwardly and through its connections with the transmitting mechanism, as hereinbefore described, will effect replenishment of filling. Owing to the floating character of the feeler which is directly mounted for movement on the feeler stand, the sensitiveness of the feeler action is emphasized, so that the feeler will partake of its side slipping character on the filling carrier or bobbin only when a minimum amount of waste remains upon the filling carrier or bobbin, and under such conditions the feeler will be positioned to cause frontward movement of the feeler stand, which consequently takes place only when the feeler detects substantial exhaustion of

filling in the shuttle and thereby effects replenishment of filling.

What is claimed is:

1. In a feeler mechanism for looms, the combination of a feeler stand, a floating side slipping feeler mounted directly on the stand for movement relative thereto towards and from the front of the loom and in a direction longitudinally of the shuttle and held from side slipping movement on detecting beats by engagement with the filling until substantial exhaustion thereof, means for supporting the feeler stand in a normal rearward position during weaving with a working supply of filling in the shuttle, and means for causing the feeler to move the feeler stand frontwardly only when the filling is substantially exhausted on a detecting beat. 70

2. In a feeler mechanism for looms, the combination of a feeler stand, a floating non-pivoted feeler mounted on the feeler stand for movement towards and from the front of the loom and in a direction longitudinally of the shuttle and held from such latter movement when a working supply of filling is present in the shuttle on detecting beats, a projection extending laterally from the floating feeler, a stop on the feeler stand to engage the projection adjacent its connection with the feeler to limit the rearward movement of the feeler, a pull spring having one end secured to the rear portion of the feeler stand and its front end secured directly to the feeler near the connection between the feeler and the laterally extending projection to move the feeler rearwardly on the feeler stand, and a stop on the feeler stand to limit the swinging movement of the feeler under the influence of the pull spring. 90

3. In a feeler mechanism for looms, the combination of a feeler stand mounted for movement towards and from the front of the loom and normally held in rearward position during weaving so long as a working supply of filling is present in the shuttle on detecting beats, a feeler mounted on the feeler stand for movement thereon towards and from the front of the loom on detecting beats during weaving with a working supply of filling in the shuttle, a spring normally acting to move the feeler rearwardly on the feeler stand, and means for causing the feeler to move the feeler stand frontwardly only when the filling is substantially exhausted on a detecting beat. 100

4. In a feeler mechanism for looms, the combination of a feeler stand, means acting to hold the feeler stand in rearward position when a working supply of filling is in the shuttle during weaving, a feeler mounted on the feeler stand for movement thereon towards and from the front of the loom when a working supply of filling is present 110

in the shuttle on detecting beats and for side slipping movement when the filling is substantially exhausted on a detecting beat, and means for engaging the feeler and feeler stand to effect frontward movement of the feeler stand when the feeler side slips on a detecting beat.

5. In a feeler mechanism for looms, the combination of a feeler stand, means acting 10 to hold the feeler stand in rearward position during weaving so long as a working supply of filling in the shuttle, a feeler mounted on the feeler stand for movement thereon towards and from the front of the loom 15 when a working supply of filling is present in the shuttle on detecting beats and for side slipping movement when the filling is substantially exhausted on a detecting beat, means for engaging the feeler and feeler stand to effect frontward movement of the feeler stand only when the feeler side slips on a detecting beat, and means for changing 20 the loom operation whenever the feeler stand is moved frontwardly.

6. In a feeler mechanism for looms, the combination of a feeler stand, a floating side slipping feeler mounted directly on the feeler stand for movement relatively thereto towards and from the front of the loom 25 when a working supply of filling is present in the shuttle on detecting beats and for side slipping movement relative to the feeler stand when the filling is substantially exhausted on a detecting beat, members on the feeler and feeler stand which are brought 30 into cooperative relation by side slipping movement of the feeler on the feeler stand to effect frontward movement of the feeler stand with the feeler when the filling is substantially exhausted on a detecting beat.

7. In a feeler mechanism for looms, the combination of a feeler stand, a floating side slipping feeler mounted directly on the feeler stand for movement relatively thereto 35 towards and from the front of the loom when a working supply of filling is present in the shuttle on detecting beats and for side slipping movement relative to the feeler stand when the filling is substantially exhausted on a detecting beat, a pull spring 40 normally acting rearwardly on the feeler, members on the feeler and feeler stand which are brought into cooperative relation by side slipping movement of the feeler on the feeler stand to effect frontward movement of the feeler stand with the feeler when the filling 45 is substantially exhausted on a detecting beat.

8. In a feeler mechanism for looms, the

combination of a feeler stand normally held 60 in rearward position during weaving so long as a working supply of filling is present in the shuttle, means connected with the feeler stand to effect replenishment of filling whenever the feeler stand is moved 65 frontwardly, a feeler mounted on the feeler stand for movement relative thereto by a working supply of filling on detecting beats and for side slipping movement when the filling is substantially exhausted on a detecting beat, and means operatively positioned by side slipping movement of the feeler to effect frontward movement of the feeler stand by the feeler as it is moved frontwardly after a side slipping movement. 70

9. In a feeler mechanism for looms, the combination of a feeler stand, a floating non-pivottally mounted side slipping feeler mounted directly upon the feeler stand for movement thereon towards and from the front of the loom and in a direction longitudinally of the shuttle, a projecting arm extended laterally from the floating feeler, a stop or pin adapted to engage the arm adjacent its connection with the feeler to limit the rearward movement of the feeler, a pull spring secured at one end directly to the feeler at a point rearward of said projecting arm and acting to move the feeler rearwardly to feeling position on the feeler stand, and a stop to limit the swinging movement of the feeler to feeling position under the influence of said spring. 85

10. In a feeler mechanism for looms, the combination of a feeler stand, a floating side slipping feeler mounted on the feeler stand for movements relative thereto in directions towards and from the front of the loom and longitudinally of the shuttle, a support for the feeler stand, yielding means acting through the support and normally holding the feeler stand in rearward position during weaving so long as a working supply of filling is in the shuttle, interengaging projections on the feeler and feeler support which are normally in inoperative relation during weaving when a working supply of filling is in the shuttle and which are operatively related by side slipping movement 100 of the feeler to effect frontward movement of the feeler stand, and means actuated to effect replenishment of filling whenever the feeler stand is moved frontwardly by the feeler. 110

In testimony whereof, I have signed my name to this specification.

EDWARD A. CUNNIFF.
